UNITED STATES PATENT OFFICE.

HARRY WARD LEONARD, OF NEW YORK, N. Y.

ELECTRIC-CIRCUIT CONTROLLER.

SPECIFICATION forming part of Letters Patent No. 878,274, dated April 30, 1901.

Application filed March 27, 1898. Serial No. 710,726. (No model.)

To all whom it may concern:

Be it known that I, HARRY WARD LEONARD, a citizen of the United States, residing in the borough of Manhattan, city of New York, in the county and State of New York, have invented certain new and useful Improvements in Electric-Circuit Controllers, of which the following is a specification.

My invention relates to the class of switches or rheostats provided with means for automatically opening or closing, regulating, or otherwise affecting or changing the condition of a circuit upon the occurrence of an abnormal increase or decrease in current to prevent injury to the translating devices in the circuit, said means being controlled or operated by electroresponsive devices.

The object of my invention is mainly to provide a circuit-controller of the character referred to with an electroresponsive device responding to abnormal increases in current, hereinafter referred to as "overload-currents," which will be effective at all times—that is, both while the controller is being operated by hand to adjust it to the normal position and after adjustment—the overload switch or controller operated or controlled by said electroresponsive device being operative to respond to an overload-current even while the switch-operating lever of the controller is being moved by the operator.

A further object is to provide an overload electroresponsive device which may be adjusted to operate whenever the current reaches or exceeds a predetermined amperage and which will become more positive and reliable as the amount of overload increases.

A further object is to provide a more reliable locking device for the overload switch or controller and means for disengaging said locking device to release said switch or controller and also means for facilitating or insuring the operation of both the overload and underload switch levers or controllers when the electroresponsive devices act.

In carrying my invention into effect I employ two independently-movable switch-levers—one designed to open or close, regulate, or otherwise affect or alter the circuit upon the occurrence of an underload-current and the other for similarly or differently affecting the circuit, but independently of the former,

upon the occurrence of an overload-current. The former is preferably held in its normal position by any suitable form of electroresponsive device, a magnet being preferred, the armature for which is carried by the switch-lever. This lever may, however, be held mechanically—by a latch, for instance—and the latch released through the agency of a magnet or solenoid. The second switch-lever is held in its normal position by a mechanical latch, the release being effected through the agency of a magnet or solenoid. The release or disengagement of the mechanical latch for the overload-switch lever and for the underload-switch lever when one is employed is preferably effected by a hammer-like blow produced by the action of the electroresponsive devices upon their armatures. In the preferred form of such devices I employ solenoids whose cores move vertically and which when actuated by the current flowing through the coils of the solenoid give a sharp blow upon the latch, which results in a quick release. The switch-levers are preferably always under spring tension, tending to move them when released. In controllers designed for handling large currents I employ knife-switches, entering spring-clips, and with such switches I preferably employ means for imparting a hammer-like blow to start them from the spring-clips when the electroresponsive devices respond to abnormal conditions in the circuit. The overload-switch is preferably provided with an auxiliary break, of carbon or other material, upon which the arc is broken. I also employ other features of construction, which will be more fully hereinafter referred to in connection with the accompanying drawings.

In the foregoing statement I have referred to a combined underload and overload switch or controller; but it will be understood that the several features of my invention are not limited to their combined use—that is to say, the devices responding to overload-currents may be separately employed in a switch or controller responding only to overload-currents, and the devices responding to underload-currents may be likewise separately employed in a switch or controller responding only to underload-currents—and all features of my invention are equally applicable to sim-

ple switches and rheostats, and particularly to rheostats employed for starting and accelerating electric motors.

The electroresponsive devices may be connected in the circuit in any suitable way. They may be connected in series or otherwise and arranged in the path of the entire current flowing to the translating device or arranged to be affected by only part of such current, or either or both devices might be in a different circuit from that in which the translating device is connected. When the apparatus is employed in the circuit of a motor, I connect the underload responsive device in most instances in series with the shunt field-winding of the motor and the overload responsive device in series with the motor-armature.

In the accompanying drawings, which illustrate my invention, Figure 1 is a plan view showing a simple form of controller or circuit-breaker; Fig. 2, a plan view of the same form of controller applied to a rheostat; Fig. 3, a plan view of a modified form of controller applied to a rheostat designed for controlling large currents. Figs. 4, 5, and 6 illustrate means for imparting a hammer-like blow to the underload-switch lever of the controller shown in Fig. 3; Fig. 7, a view like Figs. 3 and 4, but showing the means for imparting a hammer-like blow applied to the overload-switch lever; Fig. 8, a view showing the rheostat of Fig. 3 provided with means on both switch-levers for imparting a hammer-like blow; and Fig. 9, a modification showing solenoids as the over and under load electroresponsive devices, both switch-levers being held in the normal position mechanically.

Referring to the drawings, and particularly to Fig. 1, which shows the simple form of circuit-breaker, 4 and 10 represent, respectively, the independently movable underload and overload switch levers. These levers are pivoted upon a common stud having a spring 7 coiled around it and whose ends are inserted in posts carried by the lever. This spring is always under tension and tends to move the levers to the dotted-line positions 1 and 2 when released. To reduce the effect of the blow of the levers when released and to limit their movements, I provide a rubber or spring buffer 29, which in the form of controller shown in Fig. 1 is preferably carried by switch-lever 10. The underload-switch lever is provided with an operating-handle 5 and has also pivoted thereon the armature 6. This armature in the normal operative position is held by the underload-release magnet 13, provided with pole-pieces 12. The overload-switch lever 10 is provided with a pin 14, which is engaged by latch 11, pivoted upon the base-plate 26 at 15. This latch is provided with a finger projecting over a head 16, of insulating material, carried by a shank 19, which works through a non-magnetic sleeve 18, fitted within iron casing 20 and solenoid 21. The inner end of shank 19 has a small head

to prevent displacement and against which the core 24 strikes when drawn upward or inward by the action of the solenoid. The core 24 rests, normally, upon the upper end of screw 28, which works through the bottom of frame 25, secured to the casing 20. Screw 28 is locked in its adjusted position by a jam-nut 27. The head on core 24 is beveled to form a pointer or index, and the frame 25 is provided with graduations, as shown, to indicate the amperes for which the overload-release may be set. The core as shown is adjusted for forty amperes, and when the current passing through coils 21 exceeds that amount the core will be actuated, and the rapid movement of the core will give a hammer-like blow to the rod 19 and trip the latch 11. The auxiliary break for taking the arc away from the overload-switch is shown at 8. This is shown as a block of carbon carried by a spring 17, secured to a post 17^a. The auxiliary break is preferably made of carbon when the controller is intended for circuits having small currents and high electromotive forces; but when the controller is intended for circuits having large currents and low electromotive forces, and hence low resistances to consider, the carbon has so much resistance that it does not take all the arc away from the switch-contacts, and therefore I prefer in such instances to employ copper or other material of lower resistance than carbon for the auxiliary break.

The circuit connections of the controller of Fig. 1 are from binding-post 22, through coils 21 of the overload-release solenoid, to contact-plate 9 and through spring 17 to carbon block 8, then through levers 10 and 4 to contact-plate 3, and from contact-plate 3, through coils 13 of the underload-release magnet, to binding-post 23.

The normal operative position of the controller of Fig. 1 is shown in full lines. When an overload-current occurs, the release of switch-lever 10 is effected, as above described, and spring 7 moves said lever to the dotted-line position 2, thus opening the circuit at contact 9 and deenergizing both electroresponsive devices, whereupon lever 4 also becomes unlocked. The tendency of levers 4 and 10 is to move toward each other under the influence of spring 7 when released; but it will be seen that when lever 10 is released it moves a short distance before the circuit is broken, and hence that lever is in full movement before switch-lever 4 is released upon the opening of the circuit at contact 9. Therefore lever 10 will reach the dotted-line position 2 and be there arrested by buffer 29 striking lever 4 before that lever begins to move, or should lever 4 begin to move before lever 10 reaches position 2 the greater momentum of lever 10 will drive lever 4 back to its normal position when the buffer strikes it. To return lever 10 to its normal position, lever 4 is moved to the left to the dotted-line position 1, and that lever, through buffer 29 moves lever 10 before

it from position 2 to the normal position in contact with plate 9, when lever 10 will be locked in position by latch 11. Switch-lever 4 is then returned to its normal position, closing the circuit through both electroresponsive devices, and lever 4 will now be held in position by magnet 13. When an underload occurs, magnet 13 releases switch-lever 4 and spring 7 moves the lever to position 1, the movement being arrested by buffer 29, and lever 10 remaining locked in position. To close the circuit again, it is now only necessary to return lever 4 to its normal position, where, if the current is normal, it will be held again by magnet 13. If while the controller is being operated to close the circuit the current should exceed the amount for which the controller is set, the overload-switch will be released and moved away from contact 9 the instant the circuit is closed by switch 4 at contact-plate 3. If for any reason the current fails entirely or decreases abnormally while the controller is being operated to close the circuit, magnet 13 will not hold switch 4 in its closed position against the tension of spring 7 when the operator removes his hand from the operating-handle. Thus it will be seen that by employing two independently-movable switch-levers controlled by separate electroresponsive devices the circuit cannot be maintained an instant unless it is in its normal condition. It will also be seen that the arrangement which necessitates the closure of the overload-switch by means of the underload-switch, so that the former can only be closed while the latter is open, prevents all injury to the translating devices in the circuit should an overload-current occur while the controller is being operated—that is to say, by placing the operating-handle upon or interlocking it with the underload-switch lever the overload-switch lever is always free to respond instantly to an overload-current. Such would not be the case if the overload-switch were closed by hand after the underload-switch is closed, because in that case should an overload occur while the controller is being operated the damage which an overload-current would cause would actually be done before the operator could remove his hand from the operating-handle. Of course it will be understood that the switch-levers could be made to close separately and independently instead of closing the overload first by means of the underload-switch or operating lever and still accomplish my result if some means were provided whereby the underload-switch could not be closed until the overload-switch is closed, and such an arrangement would be within the scope of my invention. It will also be understood that the controller can be employed to close a circuit instead of opening a circuit, as described.

In Fig. 2 I have shown the same form of controller applied to a motor-starting rheostat and a diagram of the connections with the motor and main circuit. The contact-

buttons and resistance are shown at 30 and 31, respectively. It will be understood, however, that the resistance will be carried upon the under side of base-plate 26 and suitably protected, or it may be placed within a metal box and suitably insulated, as shown in my Patent No. 657,703, issued September 11, 1900. In this illustration, A is a double-pole switch, B the shunt field-winding of the motor, and C the armature.

The rheostat of Fig. 3 is practically the same as that of Fig. 2; but being designed for heavier currents it is desirable to provide spring-clip contacts instead of simple contact-plates for the switches to insure good contact and prevent heating. I have shown a spring-clip contact at 32 for lever 4 and at 33 for lever 10. Lever 10 in this form is made longer and pivoted in the middle. One end carries the pin for engaging the latch, and the other end carries one member of the auxiliary break. The auxiliary break in this form comprises two members—one a block of carbon 34, carried by a spring-socket 35 on lever 10, and the other member stationary copper and carbon contacts 36 and 37, respectively. Thus in breaking the circuit with this switch the current passes first through carbon and copper and then carbon and carbon. The materials employed, however, will depend upon the character of the circuit, as above explained. 29 is a buffer for lever 10, and the buffer for lever 4 is mounted upon the under side of that lever and strikes against plate 38 on lever 10.

The devices for imparting hammer-like blows to the knife-switches to start them from the stationary spring-clip contacts when the electroresponsive devices respond to abnormal conditions in the circuit are shown in Figs. 4 to 8, inclusive.

In Figs. 4, 5, and 6 I have shown three forms of devices for imparting the hammer-blow to the underload-switch lever. In Fig. 4 is shown a pivoted arm 40, having a slot 41, into which projects a pin 42 on switch-lever 4. The operating-handle 5 and armature 6 are mounted on this arm. It will be seen that when arm 40 is moved to the right switch 4 through pin 42 will be carried along with it, and in the normal position the parts will stand as shown. When arm 40 is released by magnet 13, auxiliary spring 43 will throw arm 40 backward, causing it to strike pin 42. The blow starts switch 4 from clips 32, and spring 7 will then throw the lever to the open-circuit position. In Fig. 5 arm 40 is pivoted upon switch-lever 4. The operating-handle 5 is mounted upon a cross-piece on arm 40, and which cross-piece is provided with fingers 44 and 46, projecting downwardly on opposite sides of the switch-lever. Armature 6 is also pivoted upon the cross-piece. In this form when armature 6 is released auxiliary spring 43 swings arm 40 on its pivot, causing finger 46 to strike the switch-lever, giving it a blow sufficient to start it from the slip. The weight of armature 6

in this form increases the effect of the blow. The form shown in Fig. 6 is like that of Fig. 5, except that arm 40 is pivoted upon the same stud as the switch-levers, spring 7 being secured to lever 10 and arm 40 and serving to operate the three levers, as will be evident.

In Fig. 7 I have shown the hammer-blow device of Fig. 4 applied to the overload-switch lever. In this arrangement switch-lever 10 is provided with a pin 47, which projects into a slot 48 in arm 49, which arm is pivoted upon the stud carrying levers 10 and 4. Spring 7 is secured to arm 49 and lever 4 and performs the function of spring 7 in Figs. 1, 2, and 3 in addition to imparting the hammer-blow to lever 10. The locking-latch 11 in this form engages a pin 14 on arm 49 and holds lever 10 in the normal position through the engagement of pin 47 with arm 49. When arm 49 is released by the action of overload device, spring 7 will swing arm 49 and cause it to strike pin 47, the blow starting lever 10 from spring-clip 33, and then spring 7 forces both arm 49 and lever 10 together toward lever 4. The movement is arrested by the projection on the right-hand side of lever 10 striking buffer 29, as in the construction shown in Fig. 3. To close the overload-switch, lever 4 is moved to the left, the engagement of buffer 29 on the under side of lever 4 with arm 49 moving the latter toward the left until pin 47 reaches the end of slot 48, when lever 10 will be carried along and forced into spring-clip 33.

In Fig. 8 I have shown the hammer-blow device of Fig. 5 applied to both switch-levers. Latch 11 engages with pin 14, which in this form is mounted on the cross-piece of arm 40. The buffers for arresting the switch-levers are arranged as in Fig. 3.

In Fig. 9 I have shown both switch-levers held mechanically by latches. This is illustrated only in connection with the simple form of controller shown in Fig. 1; but it will be understood that this arrangement is applicable to all the forms shown. The over-load-release is exactly the same as in Fig. 1. The underload-switch is held by the same form of latch, but the release is effected by the weight of core 50 falling upon the end of arm 51 of the latch. Core 50 is normally held within solenoid 52, and when the current fails or decreases abnormally the core will fall upon arm 51. The position of core 50 within the solenoid is determined by a screw 53, made of non-magnetic material, and by this means the current at which the core or plunger will fall can be predetermined by varying its position in the field of the coil.

The features of my controller have been described and illustrated only in connection with single-pole controllers; but it is obvious that such features may be applied to double-pole switches by simply providing the necessary number of contacts and properly insulating the several switch members or by al-

tering the form of the switch-levers, and it is evident that such a modification is within the scope of my invention. It will also be evident that by the application of well-known methods and means my improved controller may be employed on circuits of alternating currents.

While the various switches are shown with the arms moving in a plane parallel to the base-plate 26, it will be understood that in many cases it may be desirable to have the switch-levers so mounted as to move at right angles to the plane of the base-plate.

I do not claim herein the specific features shown in Figs. 3 to 8, inclusive, nor the specific means for imparting blows to switches 4 and 10, nor the combination of means for imparting blows to independently-movable switches responding to overloads and underloads, nor do I claim herein the circuit connections for a motor-starting rheostat, as shown in Fig. 2, since all those features are made the subject of a divisional application.

What I claim is—

1. In a circuit-controller, the combination of two independently-movable switch-levers, an electroresponsive device for controlling one of said levers and responding to failure or abnormal decrease of current to release said lever, means for moving said lever when released to affect the circuit, an electroresponsive device for controlling the other lever and responding to abnormal increases of current to release said second lever, and means for moving said lever when released to affect the circuit.

2. In a circuit-controller, the combination of two independently-movable switch-levers, an electroresponsive device for controlling one of said levers and responding to failure or abnormal decrease of current to release said lever, means for moving said lever when released to affect the circuit, an electroresponsive device for controlling the other lever and responding to abnormal increases of current to release said second lever, means for moving said lever when released to affect the circuit, and means for adjusting the last-named electroresponsive device for different currents.

3. In a circuit-controller, the combination of two independently-movable switch-levers, an electroresponsive device for controlling one of said levers and responding to failure or abnormal decrease of current to release said lever, means for moving said lever when released to affect the circuit, a mechanical latch for holding the other lever in its normal position, an electroresponsive device responding to abnormal increases of current to release said lever, and means for moving said lever when so released to affect the circuit.

4. In a circuit-controller, the combination of two independently-movable switch-levers, an electroresponsive device for controlling one of said levers and responding to failure or abnormal decrease of current to release

- 5 said lever, means for moving said lever when released to affect the circuit, a mechanical latch for holding the other lever in its normal position, an electroresponsive device responding to abnormal increases of current to impart a blow to said latch to release said lever, and means for moving said lever when so released to affect the circuit.
5. In a circuit-controller, the combination of two independently-movable switch-levers, an electroresponsive device for controlling one of said levers and responding to failure or abnormal decrease of current to release said lever, means for moving said lever when released to affect the circuit, an electroresponsive device for controlling the other lever and responding to abnormal increases of current to release said lever, means for moving said lever when so released to affect the circuit, and an auxiliary break in multiple with said second switch-lever.
6. In a circuit-controller, the combination of two movable switch members for controlling the same circuit, and two electroresponsive devices for controlling said switch members, each switch member and its electroresponsive device operating automatically and independently of the other to affect the same circuit, one when excessive current flows and the other upon failure or abnormal decrease of current.
7. In a circuit-controller, the combination of two levers pivotally connected, a spring constantly tending to move said levers, a latch for holding one of said levers in its normal position, an electroresponsive device for releasing said lever, and the other lever carrying a keeper and normally held by an electromagnet.
8. In a circuit-controller, the combination of an underload-switch held in its normal position by a magnet acting against a spring, an overload-switch held in its normal position by a latch against spring-pressure, and electromagnetic means acting upon overload-current to disengage said latch.
9. In a circuit-controller, the combination of an underload-switch held in its normal position by a magnet acting against a spring, an overload-switch held in its normal position by a latch against spring-pressure, electromagnetic means acting upon overload-current to disengage said latch, and an auxiliary break for the overload-switch.
10. In a circuit-controller, the combination of an overload-switch, a latch for holding said switch, a solenoid-magnet in the main current having a moving core for releasing said switch, and an underload-switch functionally connected with the overload-lever and normally held against a spring by a second magnet.
11. In a circuit-controller, the combination of two movable switch members for controlling the same circuit, said members being adapted to be held in a normal operative position and operating respectively to affect the circuit upon the occurrence of overload and underload currents, and overload and underload electroresponsive devices functionally connected with said switch members and operating independently of each other to release the overload and underload switch members respectively.
12. In a motor-rheostat, the combination of an operating-lever held in its final position through the agency of a magnet, and a solenoid-magnet the core of which is vertically movable and which upon a predetermined overload-current and independently of the first-named magnet causes the current leading to the motor-armature to be interrupted.
13. In a circuit-controller, the combination of a switch, a latch for holding said switch in its normal position, means for disengaging said latch, an electroresponsive device for controlling said means and operating under abnormal conditions in the circuit, and a second switch electrically connected in series with the first-named switch and by means of which the latter is moved into its normal position.
14. In a circuit-controller, the combination of an overload-switch lever, a latch for holding said lever in its normal position, means for disengaging said latch, an electroresponsive device for controlling said means and operating when the current exceeds a predetermined amount, and an operating-lever electrically connected in series with said switch-lever and by means of which the latter is moved into its normal position.
15. In a circuit-controller, the combination of a switch-lever, a latch for holding said lever in its normal position, means for imparting a blow to said latch to disengage the same from said switch-lever, an electroresponsive device for controlling said means and operating under abnormal conditions in the circuit, and an operating-lever electrically connected in series with said switch-lever and by means of which the latter is moved into its normal position.
16. In a circuit-controller, the combination of an overload-switch lever, a latch for holding said lever in its normal position, means for imparting a blow to said latch to disengage the same, an electroresponsive device for controlling said means and operating when the current exceeds a predetermined amount, and an operating-lever electrically connected in series with said switch-lever and by means of which the latter is moved into its normal position.
17. In a circuit-controller, the combination of a switch-lever, a latch for holding said lever in its normal position, a solenoid-magnet responding to abnormal conditions in the circuit, a movable core in said solenoid operating to impart a blow to said latch to disengage the same from said switch-lever, and an operating-lever electrically connected in series with said switch-lever and by means of which the latter is moved into its normal position.

18. In a circuit-controller, the combination with stationary switch members, of two movable switch members electrically connected in series and one being adapted to be moved by the other into its normal position, a latch for holding the former in its normal position, an electroresponsive device responding to abnormal conditions in the circuit for imparting a blow to said latch to disengage the same from said switch member, and means for moving said member when so released to affect the circuit.
19. In a circuit-controller, the combination with stationary switch members, of two movable switch members electrically connected in series and one being adapted to be moved by the other into its normal position, a latch for holding the former in its normal position, an electroresponsive device responding to abnormal increases in current for imparting a blow to said latch to disengage the same from said switch member, and means for moving said member when so released to affect the circuit.
20. In a rheostat, the combination with the resistance and contacts, of a resistance-switch, an electroresponsive device responding to abnormal conditions for controlling the movement of said switch in one direction, a second switch, means operating under abnor-

mal conditions in the circuit for automatically controlling the operation of said second switch to affect the circuit, said second switch being arranged to be moved to its normal position by the resistance-switch before the latter assumes its own normal position.

21. In an automatic circuit-breaker, the combination of an overload-switch, means for normally holding said switch in its closed position against pressure tending to open the same, an electroresponsive device for controlling said switch, said device responding to abnormal increases in the circuit, an underload-switch, means controlled by an electroresponsive device for normally holding said switch in its closed position against pressure tending to open it, said last-named electroresponsive device responding to abnormal decreases in the circuit, and electrical connections for the circuit-breaker whereby said over and under load switches and said electroresponsive devices will be electrically connected in series.

This specification signed and witnessed this 20th day of March, 1899.

HARRY WARD LEONARD.
